UNITED STATES PATENT OFFICE.

WILLIAM J. SAMSON, OF ST. LOUIS, MISSOURI, ASSIGNOR TO BEEHLER STEEL PRODUCTS COMPANY, OF ST. LOUIS, MISSOURI, A CORPORATION OF MISSOURI.

DESIGN FOR A TRUNK BOLT.

Application filed November 2, 1927. Serial No. 23,978. Term of patent 14 years.

To all whom it may concern:

Be it known that I, WILLIAM J. SAMSON, a citizen of the United States of America, residing in the city of St. Louis, in the State of Missouri, have invented a new, original, and ornamental Design for a Trunk Bolt, of which the following is a specification, reference being had to the accompanying drawing, forming a part thereof.

Fig. 1 is a front elevation of a trunk bolt, showing my new design.

Fig. 2 is a side elevation of a trunk bolt, showing my new design.

I claim:

The ornamental design for a trunk bolt, as shown.

WILLIAM J. SAMSON.
